[57] CLAIM

The ornamental design for a rocking chair, as shown and described.

DESCRIPTION

FIG. 1 is a perspective view of a rocking chair embodying my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a sectional view taken along line 6—6 of FIG. 2; and

FIG. 7 is a sectional view taken along line 7—7 of FIG. 2.

The design is characterized by the specific configuration of the rocker members as best illustrated in FIG. 7.

FIG. 1.

FIG. 2.

FIG. 6.

FIG. 7.

FIG. 3.

FIG. 4.

FIG. 5.
